BREATHER VALVE

John D. Crecca, United States Navy, and
Stephen M. Phillips, Westbury, N. Y.

Application October 18, 1934, Serial No. 748,862

6 Claims. (Cl. 277—61)

(Granted under the act of March 3, 1883, as
amended April 30, 1928; 370 O. G. 757)

This invention relates to a breather valve for permitting the escape of air when filling the tank or container, such as a tank, tank car, tank truck, tank ship, or the like, with a liquid and for the admission of air to the foregoing containers or compartments therein when removing the liquid therefrom by means of a pump or other device, while at the same time excluding the admission of water, rain water, sea water, spray, or other foreign matter to the tank or compartment in question at all times during the operation of either expelling or taking in air.

The particular application of the device in question is for attachment directly or by means of piping to fuel oil tanks or tanks used for the storage of fuel oil and similar fluids or materials loaded into a tank or removed therefrom while in a fluid state aboard ships and sea-going vessels, and to permit the filling or pumping down of such tanks under all conditions of weather with the decks of the vessel awash or flooded from the sea, or in any other manner, without permitting any of the accumulated water to enter the said tanks in which the fuel oil or other liquid subject to contamination is stored.

The further object of this invention is to simplify the construction and reduce the weight of a breather valve, that will fulfill the foregoing requirements, to a minimum.

30 The further object of this invention is to permit attachments of the breather valve directly to a ship's deck or bulkhead by means of welding or with a very short section of pipe in such manner as will permit it to be installed in obscure corners and without necessitating long lengths of pipe to raise it above the height of a normal sea washing over the deck.

A further object is to regulate the pressure or vacuum, under which the respective valves are to operate, from a position external to the valve and thus without dismantling the valve. The pressure valve or vacuum valve of the breather valve can be regulated independently and separately.

With the above and other objects in view, the invention consists in the construction, combination and arrangements of parts as will hereinafter be more fully described and as shown in the accompanying drawing, wherein:

The figure is a section view of the valve schematically shown in operative position.

There is shown at 10 a valve body, preferably made of brass, which is provided with a gooseneck flange 11 threaded as at 12, that may be secured to a vent or breather pipe 13 leading through the roof or deck 14 to a compartment or tank 15. The

compartment or tank 15 is intended to receive liquids such as fuel oil, gasoline, or other materials, the level 16 of which may vary as the material is refilled or consumed and as the temperature rises or falls.

Tanks or compartments of this nature are generally made to stand a pressure of at least four pounds per square inch and as the level rises or falls due to temperature variations or to consumption or replacement, it is necessary that the 10 vent pipe 13 allow excessive pressure within the tank to relieve itself as the temperature rises or as the material is being replaced and also allow the vacuum created therein by falling temperature or consumption of material to likewise relieve itself, so as to prevent exploding or collapsing of the tank wall. It is also necessary that when the material 16 is inflammable material that the fumes created and discharged as the pressure is relieved should be discharged in a position 20 where they will not be confined so as to cause a fire hazard.

The breather valve 10 attached to the pipe 13 performs these functions and may be placed, in the case of a vessel, on the lowest weather deck 25 and may operate, in spite of the fact that seas may wash thereover, without allowing any contamination to enter the tank through the valve. By being placed on the lowermost weather deck, an excessive length of vent pipe 13 is avoided. 30

The valve body 10 is provided with an inlet or vacuum relief valve 17 which seats as at 18 against the removable valve seat 19 threaded as at 20 into the valve body 10. In order to decrease the fire hazard, a protective cover 21 is removably threaded as at 22 to the valve body 10 and includes a fire-resistant bronze gauze 23 therewith. To gain access to the valve 17 for adjusting purposes it is only necessary that this protective cover 21 and gauze 23 be temporarily 40 removed.

The pressure at which the valve 17 will relieve the vacuum is controlled by means of an adjustable spring 24 held against the bottom of the valve 17 by means of the spring seat 25 threaded 45 as at 26 through the spider 27 within the valve body. In order to adjust the spring seat 25 so as to vary the tension on the spring 24, the valve stem 28 is provided with a key 29 which slides in the key-way 30 in the spring seat 25. This 50 valve stem 28 may be rotated by an appropriate tool such as a screw driver placed within the kerf or slot 31 which extends through inlet valve 17. As will be observed the inlet valve 17 is recessed so as to countersink the enlarged head 55

32 of the valve stem 28 and then this head 32 is secured immovably in position relative to the inlet valve 17 by a ring 33 threaded as at 34 into the inlet valve 17.

5 It will be furthermore observed that the contour of the inlet valve 17, its seat 19, and the upper portion of the valve body 10, as an assembly, is convex so that any water, rain water, sea water, spray, or the like that may be deposited thereon will normally shed itself therefrom due to the shape.

15 The pressure relief or outlet valve 35 is placed vertically below the inlet valve 17 and seats against a removable seat 36 threaded as at 37 to the bottom of the valve body 10. A protective cover 38 and flame-resistant gauze 39 similar to the protective cover 21 and flame-resistant gauze 23 are threaded as at 40 to the bottom of the valve body 10 and is removable therefrom to allow access to the outlet valve 35 for easy adjustment thereof. In order to easily adjust the operating tension of the outlet valve 35 it is provided with a sleeved valve stem 41, the end 46 of the inlet valve stem 28 being slidably received within the stem 41 so that each stem acts as a guide for the other stem. The sleeve stem 41 is externally threaded as at 47 so as to adjustably receive a spring seat 48 thereon as shown, the spring seat 48 being provided with guide 25 fingers 49 which operate against the guide bars 50 integrally projecting from the valve body 10 so as to cause longitudinal displacement of the spring seat 48 relative to the valve stem 41 as the valve 35 is rotated by means of an appropriate tool such as a screw driver placed within the kerf or slot 51.

30 Lugs 52, projecting internally from the valve 36, provide a companion spring seat for a compression spring 53 secured between these lugs 52 and the adjustable spring seat 48. The valve body 10 is further provided with a threaded drain 40 53 which may be opened by the knurled head 54 so as to bring the threaded plug 55 sufficiently far out to allow any water collected in this 45 trough-shaped bottom to drain therefrom through the vent 56 in the plug.

35 In operation, the set pressure at which both the inlet and outlet valves may operate may be easily and quickly adjusted independently of each other by merely removing their respective covers and fire-resistant gauze and operating a screw driver within the proper kerf.

40 When the pressure in the tank or compartment 55 exceeds that of the set resistance of the spring 53, the outlet valve 35 will open and the pressure, as well as any moisture that may have collected therein, escape therethrough. In a similar way, whenever the vacuum within the tank becomes greater than that of the set pressure 60 sure of the spring 24 of the inlet valve 17, the inlet valve 17 will open and allow the atmosphere to enter therethrough. Any water or spray carried in the entering atmosphere will be deflected by the centrifugal action of the air within the 65 circular entrance mouth 57 and cause it to drop into the trough 58 leading to the outlet valve 35, the air passing from the mouth through the gooseneck extension 11 through the breather or vent pipe 13.

70 Due to the convexity of the inlet valve assembly a minimum amount of moisture will be drawn 75 therein and this, as already explained, will accumulate and may be discharged either by manual opening of the plug 55 or by automatic opening of the outlet valve 35. Due to this facility for

discharging any accumulated moisture the valve 10 may be placed on the weather deck of a ship or above the roof of a tank car so that any fumes discharged thereby will be discharged in the open and carried away by the wind so as not 5 to collect in a confined place and cause a fire hazard.

The invention described herein may be manufactured and used by or for the Government of the United States of America for governmental 10 purposes without the payment of any royalties thereon or therefor.

We claim:

1. A breather valve comprising a valve body adapted to be secured to a vent pipe extending 15 through a wall or deck, said breather valve comprising a gooseneck extension and a valve body proper, a circular inlet mouth located at the top of said valve proper, a trough formed at the bottom of said valve proper below said inlet mouth, 20 an inlet valve seating within said inlet mouth, said inlet mouth discharging any entrained foreign matter in the air to said trough member, an outlet valve, a valve stem on said inlet valve, and a valve stem on said outlet valve, one of said 25 valve stems being in the form of a sleeve adapted to slidably receive and guide the other of said valve stems.

2. A breather valve comprising a valve body adapted to be secured to a vent pipe, said breath- 30 er valve comprising a gooseneck extension and a valve body proper, a circular inlet mouth located at the top of said valve proper, a trough formed at the bottom of said valve proper below said inlet mouth, an inlet valve seating within 35 said inlet mouth, said inlet mouth discharging any entrained foreign matter in the air to said trough member, an outlet valve, a valve stem on said inlet valve, a valve stem on said outlet valve, one of said valve stems being in the form of 40 a sleeve adapted to slidably receive and guide the other of said valve stems, compression spring means for holding said inlet valve and said outlet valve in closed position, and means for adjusting the compression of said compression spring 45 means, said adjusting means being easily accessible exteriorly of said valve body while said valves remain in operative position.

3. A breather valve comprising a valve body adapted to be secured to a vent pipe extending 50 through a wall or deck, said breather valve comprising a gooseneck extension and a valve body proper, a circular inlet mouth located at the top of said valve proper, a trough formed at the bottom of said valve proper below said inlet mouth, 55 an inlet valve seating within said inlet mouth, said inlet mouth discharging any entrained foreign matter in the air to said trough member, an outlet valve, a valve stem on said inlet valve, a valve stem on said outlet valve, one 60 of said valve stems being in the form of a sleeve adapted to slidably receive and guide the other of said valve stems, compression spring means for holding said inlet valve and said outlet valve in closed position, means for adjusting the compression of said compression spring means, said 65 adjusting means being easily accessible exteriorly of said valve body while said valves remain in operative position, and water draining means adjacent the bottom of said valve body. 70

4. A breather valve comprising a valve body adapted to be secured to a vent pipe extending through a wall or deck, said breather valve comprising a gooseneck extension and a valve body proper, a circular inlet mouth located at the top 75

of said valve proper, a trough formed at the bottom of said valve proper below said inlet mouth, an inlet valve seating within said inlet mouth, said inlet mouth discharging any entrained foreign matter in the air to said trough member, an outlet valve, a valve stem on said inlet valve, a valve stem on said outlet valve, one of said valve stems being in the form of a sleeve adapted to slidably receive and guide the other of said valve stems, an inlet valve seat located at the top of said valve body, and an outlet valve seat located at the bottom of said valve body.

5. A breather valve comprising a valve body adapted to be secured to a vent pipe, said breather valve comprising a gooseneck extension and a valve body proper, a circular inlet mouth located at the top of said valve proper, a trough formed at the bottom of said valve proper below said inlet mouth, an inlet valve seating within said inlet mouth, said inlet mouth discharging any entrained foreign matter in the air to said trough member, an outlet valve in said trough member,

10

15

20

said outlet valve automatically discharging any entrained foreign matter in the trough member at each operation thereof.

6. A breather valve comprising a valve body adapted to be secured to a vent pipe, said breather valve comprising a gooseneck extension and a valve body proper, a circular inlet mouth located at the top of said valve proper, a trough formed at the bottom of said valve proper below said inlet mouth, an inlet valve seating within said inlet mouth, said inlet mouth discharging any entrained foreign matter in the air to said trough member, an outlet valve in said trough member, said outlet valve automatically discharging any entrained foreign matter in the trough member at each operation thereof, and manually controllable means in said trough member for discharging the entrained foreign matter therefrom, should said inlet valve fail to operate at sufficiently frequent intervals.
